UNITED STATES PATENT OFFICE.

GEORGE P. WIGGINTON, OF KALAMAZOO, MICHIGAN.

BINDER DEVICE.

1,150,471.

Specification of Letters Patent. Patented Aug. 17, 1915.

Application filed August 27, 1914. Serial No. 858,970.

To all whom it may concern:

Be it known that I, GEORGE P. WIGGINTON, a citizen of the United States, residing at Kalamazoo, Michigan, have invented certain new and useful Improvements in Binder Devices, of which the following is a specification.

This invention relates to an improvement in binder devices.

10 The main objects of this invention are: First: to provide an improved support for temporary binders or loose sheet holders which greatly facilitates the removal and insertion of sheets or leaves and supports 15 the binder so that all the sheets are accessible. Second: to provide an improved binder device adapted as a support for binders of the post type, and also as an adjusting means for the binder. Third: to provide an im- 20 proved binder device having these advantages which is comparatively simple and economical in structure and very easy to operate.

Further objects, and objects relating to 25 structural details, will definitely appear from the detailed description to follow.

I accomplish the objects of my invention by the devices and means described in the following specification.

30 The invention is clearly defined and pointed out in the claims.

A structure which is a preferred embodiment of my invention is clearly illustrated in the accompanying drawing, forming a 35 part of this specification, in which:

Figure I is a plan view of a binder device, embodying the features of my invention. Fig. II is a detail side elevation of the structure shown in Fig. I, with a binder of 40 the sectional post type in position therein. Fig. III is a detail vertical longitudinal section on a line corresponding to line 3—3 of Fig. I, with a binder shown in position in the holder. Fig. IV is an enlarged detail 45 view, partially in transverse vertical section, on a line corresponding to line 4—4 of Figs. II and III. Fig. V is an enlarged detail section on a line corresponding to line 5—5 of Figs. III and VI, showing details 50 of the mounting for the adjusting screw. Fig. VI is a detail longitudinal section on a line corresponding to line 6—6 of Figs. III and V. Fig. VII is an enlarged detail rear view of the split nut, the screw being shown 55 in section, the nut being in its closed or engaging position. Fig. VIII is a detail view

similar to that of Fig. VII with the nut in its disengaging or open position. Fig. IX is a detail view, partially in section, showing details of the nut engaging and disengaging cam. Fig. X is an enlarged detail section of the nut engaging and disengaging cam taken on a line corresponding to lines 10—10 of Figs. III, IV and VII. Fig. XI is a detail section on a line corresponding to line 11—11 of Fig. III showing the mounting of the posts.

In the drawing, similar reference characters refer to similar parts throughout the several views, and the sectional views are 70 taken looking in the direction of the little arrows at the ends of the section lines.

Referring to the drawing, the base 1 of the binder support is provided with a longitudinal slot 2 having grooves 3 in its edges. 75 At one end of the base is a fixed support 4 comprising a pair of uprights connected by a cross piece. This support is inclined outwardly to support one of the covers 5 of the binder in an outwardly inclined position. 80 A movable support 6 is provided for the other binder cover 7. The movable support is provided with a slide 8 disposed in the slot 2, and provided with lugs 9 engaging the grooves 3. The binder covers 5 and 7 85 are provided with binding members 10 and 11 respectively, the posts 12 of the structure illustrated being sectional posts and removably secured to the binding member 10 by means of their reduced screw threaded ends 90 13. The binding member 11 has holes 14 therethrough adapted to receive the posts and is adjustable thereon and provided with means for securing it in its adjustable positions on the posts, the structure illustrated being 95 provided with a locking bar 14 actuated by means of a key 15. As the details of this securing means form no part of my invention, I do not further illustrate or describe the same herein, satisfactory mechanisms 100 being well known in the art.

The movable support 6 has holes 15 therein adapted to receive the posts 12, as shown in Figs. III and IV. The movable support is adjusted by means of the screws 16 disposed longitudinally of the slot 2 and passing through the slide 8. The screw is journaled in bearings 17 at the ends of the slot. The screw projects at one end of the base and is adapted to receive an actuating key, 110 not shown.

In the structure illustrated, the slide is

detachably connected to the screw by means of a split nut, consisting of sections 18 pivotally mounted on the slide at 19 to be moved to and from the screw as shown in Figs. VII and VIII. The actuating cam 20 is seated in a cavity 21 in the slide, and is provided with cam slots 22 engaged by pins 23 on the nut members 18. The cam member has a central slot 24 adapted to receive a key, not shown. By turning this cam member in one direction the nut members are swung to their disengaging positions, as shown in Fig. VIII, and by turning it in the opposite direction they are engaged, as shown in Fig. VII. The cam member also serves as an effective means for retaining the nut sections in their engaged and disengaged positions. The posts may, if desired, be entirely removed when the binder is in the holder so that the sheets are all free although ordinarily this is not required as the binder is supported so that the sheets can be readily manipulated to disengage them from the posts.

With the parts arranged as described, the supports may be adjusted to receive the binder and support its covers and sheets in position so that they are fully accessible and may be readily removed and reinserted or new sheets inserted as desired.

One of the objections to post binders which are not provided with means for securing clamping adjustment is that it is not possible to clamp the sheets as tightly as desirable, as the only means for adjusting is by pushing the binding member together and securing in position. With my improved binder support device, the binding members may be clamped upon the sheets and secured, and the movable support moved back to release the binder, the device being desirable for use in connection with binders of the projecting post type, as illustrated, and also certain binders of the telescoping post type which are without means for clamping adjustment of the binding members.

My improved binder device is adapted for use in connection with various types of binders as will be readily understood.

I have illustrated and described my improvements in detail in a simple and practical embodiment. I have not attempted to illustrate or describe various modifications which might be desirable to adapt same, to a particular type of binder or to meet particular requirements as I believe the disclosure made will enable those skilled in the art to which my invention relates to embody or adapt the same as conditions may require. I desire, however, to be understood as claiming my improvements specifically in the form illustrated as well as broadly within the scope of the appended claims.

Having thus described my invention, what

I claim as new and desire to secure by Letters Patent, is:

1. The combination with a temporary binder comprising binding members, and posts, said posts being detachably mounted on one of said binding members, the other binding member being adjustable on said posts and provided with means for securing it in its adjusted positions, of a base, a pair of supports on said base one of which is adjustably mounted and provided with holes adapted to receive said binder posts, said posts being removable through said holes, an adjusting screw for said movable support, a split nut on said movable support coacting with said screw, and means for engaging and disengaging said nut, said movable support being freely movable when said screw and nut are disengaged, all coacting for the purpose specified. 75

2. The combination with a temporary binder comprising binding members, and posts, said posts being mounted on one of said binding members, the other binding member being adjustable on said posts and provided with means for securing it in its adjusted positions, of a base, a pair of supports on said base one of which is adjustably mounted and provided with holes adapted to receive said binder posts, an adjusting screw for said movable support, a split nut on said movable support coacting with said screw, and means for engaging and disengaging said nut, said movable support being freely movable when said screw and nut are disengaged, all coacting for the purpose specified. 85

3. The combination with a temporary binder comprising binding members, and posts, said posts being detachably mounted on one of said binding members, the other binding member being adjustable on said posts and provided with means for securing it in its adjusted positions, of a base, a pair of supports on said base one of which is adjustably mounted and provided with holes adapted to receive said binder posts, said posts being removable through said holes, and an adjusting screw for said movable support, all coacting for the purpose specified. 105

4. The combination with a temporary binder comprising binding members, and posts, said posts being mounted on one of said binding members, the other binding member being adjustable on said posts and provided with means for securing it in its adjusted positions, of a base, a pair of supports on said base one of which is adjustably mounted and provided with holes adapted to receive said binder posts, and an adjusting screw for said movable support, all coacting for the purpose specified. 125

5. The combination with a temporary binder comprising binder members, and

- posts, said posts being detachably mounted on one of said binding members, the other binding member being adjustable on said posts, of a base, a pair of supports on said base one of which is adjustably mounted and provided with holes adapted to receive said binder posts, said posts being removable through said holes, and means for adjusting said movable support, all coacting for the purpose specified.
6. The combination with a temporary binder comprising binding members, and posts, said posts being mounted on one of said binding members, the other binding member being adjustable on said posts, of a base, a pair of supports one of which is adjustably mounted on said base and provided with holes adapted to receive said binder posts, and means for adjusting said movable support, all coacting for the purpose specified.
7. The combination with a temporary binder comprising covers and binding members, of a support therefor comprising a base, support members mounted on said base, one of said members being adjustable, means for adjusting said adjustable support whereby it may be adjusted to support the binder in its open position or to adjust said binding members.
8. A support for temporary binders comprising a base having a longitudinal slot therein, the edges of the slot being grooved, a fixed support on said base, a movable support, a slide for said movable support disposed in said base slot and having lugs engaging the grooves in the edges thereof, a screw disposed longitudinally of said slot and journaled at the ends thereof, a split nut on said slide coacting with said screw, and means for engaging and disengaging said nut, said movable support slide being freely movable when said screw and nut are disengaged.
9. A support for temporary binders comprising a base having a longitudinal slot therein, a fixed support on said base, a movable support, a slide for said movable support disposed on said base slot, a screw disposed longitudinally of said slot and journaled at the ends thereof, a split nut on said slide coacting with said screw, and means for engaging and disengaging said nut, said movable support slide being freely movable when said screw and nut are disengaged.
10. A support for temporary binders comprising a base having a longitudinal slot therein, the edges of the slot being grooved, a fixed support on said base, a movable support, a slide for said movable support disposed in said base slot and having lugs engaging the grooves in the edges thereof, and a screw for adjusting said slide longitudinally of said slot.
11. A support for temporary binders, comprising a base provided with a pair of supports, one of said supports being movable, a screw for adjusting said movable support, a split nut connecting said support with said screw, and means for engaging and disengaging said nut, said movable support being freely movable when said screw and nut are disengaged.
12. The combination with a temporary binder comprising binding members and posts, of a base having a longitudinal slot therein, a pair of supports mounted on said base, one of said supports being movable, said posts being removable through one of said supports, a slide for said movable support disposed in said longitudinal slot in said base, and a screw for adjusting said movable support disposed in said slot to engage said slide so that the base is unobstructed thereby.
13. The combination with a temporary binder comprising covers and binding members associated to be adjusted relative to each other, of a support therefor comprising a base provided with a pair of supports, one of said supports being movable on said base, said supports being provided with parallel bottom portions adapted to support the binding members in a substantially parallel relation and with diverging upper portions adapted to support the covers, and a screw means for adjusting said movable support to adjust the binding members or to support the binder in open position.
14. The combination with a temporary binder comprising covers and binding members associated for adjustment relative to each other, of a support therefor comprising a base provided with a pair of supports, one of said supports being movable, said supports being provided with vertical portions adapted to support the binding members and with diverging upper portions adapted to support the covers, and means for adjusting said movable support whereby the binding members may be adjusted or the covers supported in open position.
15. The combination with a temporary binder comprising covers and binding members associated for adjustment relative to each other, of a support therefor comprising a base provided with a pair of supports, one of said supports being movable, said supports being provided with portions adapted to support the binding members and with diverging upper portions adapted to support the covers whereby the binding members and covers are adjustably supported.
16. The combination with a temporary binder comprising binding members and posts, of a base, a pair of supports one of which is adjustably mounted on said base and provided with openings adapted to receive said posts, and means for adjusting said movable support.

17. The combination with a temporary binder comprising binding members and posts, said posts being detachably mounted on one of said binding members, the other binding member being adjustable on said posts, of a base, and a pair of supports on said base, one of which is provided with holes adapted to receive said posts, said posts being removable through said holes, one of said supports being adjustable on said base, all coacting for the purpose specified.

18. The combination with a temporary binder comprising binding members and removable posts, of a base, a pair of supports one of which is adjustably mounted on said base, said posts being removable through one

of said supports, and means for adjusting said movable support.

19. The combination with a temporary binder comprising binding members and removable posts, of a base, a pair of supports one of which is adjustably mounted on said base and provided with openings through which said posts may be removed, and means for adjusting said movable support. 20 25

In witness whereof, I have hereunto set my hand and seal in the presence of two witnesses.

GEORGE P. WIGGINTON. [L.S.]

Witnesses:

OSCAR ALLYN,
EMMA L. HARRIS.

It is hereby certified that Letters Patent No. 1,150,471, granted August 17, 1915, upon the application of George P. Wigginton, of Kalamazoo, Michigan, for an improvement in "Binder Devices," were erroneously issued to the inventor, said Wigginton, whereas said Letters Patent should have been issued to *Kalamazoo Loose Leaf Binder Company, of Kalamazoo, Michigan*, as assignee of the entire interest in said invention, as shown by the records of assignments in this office; and that the said Letters Patent should be read with this correction therein that the same may conform to the record of the case in the Patent Office.

Signed and sealed this 21st day of September, A. D., 1915.

[SEAL.]

J. T. NEWTON,
Acting Commissioner of Patents.
